UNITED STATES PATENT OFFICE.

FRANK W. BURTON, OF SAN DIEGO, CALIFORNIA.

ORNAMENTAL CAP.

1,055,706.

Specification of Letters Patent. Patented Mar. 11, 1913.

Application filed September 3, 1912. Serial No. 718,271.

To all whom it may concern:

Be it known that I, FRANK W. BURTON, a citizen of the United States, residing at San Diego, in the county of San Diego and 5 State of California, have invented certain new and useful Improvements in Ornamental Caps, of which the following is a specification.

This invention relates to caps for covering the heads of screws, nails, bolts, and similar fastening means, and some of the objects of my improvement are, simplicity of construction, facility of use, and comparative inexpensiveness of manufacture. 15 These and other objects I attain by means of the device illustrated in the accompanying drawings, in which:

Figure 1 is a top plan view in pyramidal form; Fig. 2, a side elevation of the same; 20 Fig. 3, a central vertical section of the same; Fig. 4, a top plan view of spherical form; Fig. 5, a side elevation of the same; Fig. 6, a top plan view of conical form; Fig. 7, a side elevation of the same; Fig. 8, a top 25 plan view of the plate or washer, of square form; Fig. 9, the same, of circular form; and, Fig. 10, a bottom plan view of the pyramidal form.

Similar reference numbers refer to similar parts throughout the several views of the drawings.

The cap, 1, is made in some ornamental shape, such as pyramidal, hemispherical, conical, etc., and is preferably stamped from 35 sheet metal. The base perimeter is planed off so that the outer surface of the cap extends downward to the surface of the object upon which it is applied, as shown at 2. On the base perimeter, and preferably integral, 40 are formed centripetally extending tongues, 3. The inner edge of these tongues is beveled, as shown at 4.

A flat plate, 5, is provided, of the shape of the base of its corresponding cap and 45 adapted to fit into the base of cap 1 and form a bottom therefor, so that the under surface of the plate is flush with the bottom edge of the cap. The plate is formed with a central hole, 6, by which it is fastened to 50 an object to which it is to be applied, being used after the manner of a washer or bur for a bolt, nail or screw, 7, or similar fastening means (Fig. 3). At the perimeter the plate 5 is formed with upward-extend-

ing catches, 8. The catches 8 are so formed 55 that tongues 3 of cap 1 may catch under them (Fig. 3).

In use, the plate 5 is applied under the head of a bolt or other fastener and is securely drawn up to the surface of the object 60 to which it is applied, and the entire under surface fits closely against the surface of the object. The cap 1 is now applied by slipping one of the tongues 3 under one of the catches 8 and pressing the cap over the 65 plate so that the opposite tongue 3 snaps over the corresponding catch 8.

It will be understood that in thus snapping over the catch the wall of the cap 1 springs outward sufficiently to permit the 70 tongue 3 to pass catch 8 and then springs in under the catch. The cap is now securely held by the plate 5 by means which are hidden within itself. The cap may be removed at any time by prizing it up with a sharp- 75 edged instrument inserted between its edge and the surface of its support.

It will now be seen that the invention may be made in ornamental form, may be cheaply manufactured, and may be easily applied in 80 use.

Having thus described my invention so that any one skilled in the art pertaining thereto may make and use it, I claim:

1. A cap for screws, nails, and the like, 85 comprising a washer held securely under the head of a screw, nail, or like fastening means, said washer provided with catch members on its perimeter, and an ornamental cap provided with tongues at its base 90 extending toward the center to serve as catch members to catch on said catch members formed on said washer.

2. A cap, comprising a plate, formed with a central hole to receive a bolt or similar 95 fastening means and up-turned catch members on its perimeter, and a cap adapted to fit over said plate and integral tongues on its perimeter, extending toward the center, adapted to catch over and hold said cap on 100 said plate when pressed theron.

In witness whereof, I have hereunto subscribed my name in the presence of two subscribing witnesses.

FRANK W. BURTON
